C. ZULVER

LIQUID FUEL BURNER OR ATOMIZER

Filed July 30, 1924

Inventor
Cornelis Zulver
by Wilkinson & Giusta
Attorneys.

UNITED STATES PATENT OFFICE.

CORNELIS ZULVER, OF LONDON, ENGLAND.

LIQUID-FUEL BURNER OR ATOMIZER.

Application filed July 30, 1924. Serial No. 729,161.

To all whom it may concern:

Be it known that I, CORNELIS ZULVER, engineer, a subject of the Queen of the Netherlands, of St. Helens Court, Great St.

5 Helens, in the city of London, England, have invented a new and useful Improvement in or Relating to Liquid-Fuel Burners or Atomizers, of which the following is a specification.

10 The object of this invention is to provide an improved liquid fuel burner or atomizer of the type wherein mechanically operated atomizers are employed and to dispense with the ordinary filters, high pressure heaters 15 and pumps which are at present used for liquid fuel burners of the ordinary type working under the direct pressure system.

A further object is to so arrange the improved burner that pulverized fuel may be 20 fed thereto instead of the oil or together therewith as circumstances may require.

25 One type of burner has been proposed wherein the oil is atomized by a device mechanically driven by an external motor or the like and consisting of a rotary cup into which the oil is fed the delivery edge of said cup being arranged within the exit of a surrounding air nozzle.

30 In another type of burner oil is discharged from the open or nozzle end of an oil supply tube on to a freely mounted fan like atomizer rotated by the blast of air passing through the burner.

In the improved burner the oil fuel in 35 passing through the oil supply tube is subjected therein to the action of a rotary spindle passing longitudinally through the oil tube and driven by an external motor or other source of power, and the oil on leaving the open end or nozzle of the oil supply tube is subjected to the mechanical beating action of blades mounted on the end of said power driven spindle beyond the open end or nozzle of the said oil supply 45 tube.

The said power driven spindle may be fitted at suitable points in its length as well as at the end with blades or like devices adapted to break up and discharge the oil 50 together with any impurities which may come from the supply and thereby avoid the clogging of the burner.

The spindle may be mounted on ball or roller bearings.

55 The oil is fed by gravity or pressure from a tank where it is heated approximately to

its flash point by means of suitable steam coils or otherwise as required.

The outlet end of the oil tube may be flared outwardly or contracted inwardly or 60 fitted with any suitable form of nozzle.

The accompanying drawing is a sectional elevation showing one construction of the improved oil burner fitted to a furnace front.

In the construction illustrated an oil supply tube *a* preferably tapered towards its discharge end is fitted with a rotary spindle *b* which extends longitudinally and centrally through the horizontal outlet end portion of said tube and passes out through 70 the rear wall thereof where ball bearings *c* are provided.

The rotary spindle *b* projects beyond the open or discharge end of the oil tube *a* and is fitted with a series of blades *b'* adapted 75 to mechanically atomize the oil which issues from the oil tube, the outlet from which is of such dimensions as to freely pass any impurities in the oil.

The said oil tube or nozzle *a* is enclosed 80 in an air supply pipe *d* and the spindle *b* is extended rearwardly and passes out through the rear wall of the said air tube where ball bearings *d'* and a suitable stuffing box *d''* are provided. The spindle *b* is driven by 85 means of an electric motor *e* suitably supported and preferably coupled to a fan *f*, so that the said motor *e* may be employed not only for driving the said spindle *b* but also the fan *f* which supplies air under pressure to the tube *d*.

The air supply tube *d* extends forwardly 90 so as to discharge into the furnace and is preferably tapered towards its front end which is provided with an outwardly flared 95 nozzle *d''*. The said nozzle *d''* is surrounded by a series of air cones *g', g'', g'''*, for admitting an additional supply of air to the furnace around the oil burner from the usual air heating space *h* in the furnace front. 100 In order to admit heated air to the cones *g', g'', g'''*, a series of openings *h', h'', h'''* or the like are provided in the entrance chamber walls.

The interior of the air supply tube *d* is 105 fitted with converging cones *i, j*, the first *i* located in front of the oil tube *a* and the other *j* located further forward and beyond a lateral opening *k* by which solid pulverized fuel may be admitted to and drawn 110 through the air tube *j* by induction and discharged into the furnace.

In operation oil is fed to the oil supply tube *a* by gravity or pressure, and heated air under pressure is supplied to the air tube *d* from the fan *f*, the said air supply being regulated by the air valve *d*⁴.

The spindle *b* is rotated by the electric motor *e* so that the oil discharged from the outlet of the tube *a* is atomized by the combined mechanical action of the rotary spindle *b* and blades *b*' on the tip thereof and the heated air under pressure supplied from the fan *f*. The atomizing action is enhanced by the series of cones *i j* in the air tubes *d* and the additional air cones *g' g² g³* surrounding the nozzle end thereof.

Air supplied by fan *f* may be heated in any suitable manner, for example, by passing the supply pipe through a casing formed in the furnace front, thereby utilizing heat which would otherwise be lost by radiation, or any other convenient manner for heating the air may be employed.

If it is desired to admit pulverized solid fuel with the atomized oil the inlet *k* is connected to a suitable receptacle containing the pulverized solid fuel which is drawn into and forced through the burner by induction. When not employed for the admission of pulverized solid fuel the inlet *k* may be closed or used as an additional air inlet.

Under certain circumstances where it is necessary or desirable to temporarily feed the furnace with pulverized solid fuel alone the oil jet may be shut off or steam or air may be supplied through the oil pipe to assist in the injection of the pulverized solid fuel and air into the furnace. The improved burner thus lends itself to ready conversion from oil firing to firing with pulverized fuel or both as required.

The improved burner may be fitted to an ordinary fire door and arranged to work with forced or natural draught as desired.

The burner spindle may revolve at from 1,000 to 4,000 revolutions per minute, more or less as may be found most suitable.

What I claim as my invention and desire to secure by Letters Patent is:—

50 1. A fuel burner comprising the combination of an oil nozzle, an air pressure chamber surrounding said oil nozzle, said air chamber extending forwardly of said nozzle and converging toward its forward end, an oil atomizer mounted at the forward end of said oil nozzle, said atomizer extending rearwardly through said oil nozzle and air chamber, anti-friction bearings mounted in said oil nozzle and said air chamber, means for mechanically turning said atomizer, and a plurality of converging air chambers adapted to regulate air to be mixed with said oil.

60 2. A fuel burner comprising an oil nozzle, an air chamber surrounding said oil

nozzle, a rotatable atomizer mounted in said oil nozzle and adapted to spray the oil in said air chamber, means for rotating said atomizer, and a plurality of converging telescoping air chambers for controlling the combustion of oil passing therethrough.

65 3. A fuel burner comprising an oil supply pipe, an air supply chamber, an atomizer positioned within said oil pipe, said atomizer having a rotatable shaft, a pair of anti-friction bearings for said shaft, one of said bearings being mounted in said oil supply pipe and the other of said bearings mounted in the outer wall of said air supply chamber, a plurality of atomizing blades mounted on said shaft and adapted to rotate therewith, and a plurality of air controlling chambers through which the atomized oil is adapted to pass.

70 4. A fuel burner comprising an oil supply pipe, an air pressure chamber surrounding said pipe, a rotatable atomizer mounted within said oil pipe, said atomizer extending rearwardly through said oil pipe and said air chamber, means for rotating said atomizer, a pulverized fuel chamber surrounding the forward end of said air chamber, said pulverized fuel chamber having a converting forward end, and a plurality of mixing chambers mounted forwardly of said pulverized fuel chamber for controlling the air content of the fuel passing therethrough.

75 5. A fuel burner comprising an oil supply section and a solid fuel supply section, said oil section having mechanical atomizing means for atomizing the oil, an air pressure chamber surrounding said atomizer, an air and oil mixing chamber mounted forwardly of said atomizer, said mixing chamber having tapering walls, said solid fuel supply section comprising a supply pipe and a mixing chamber, said mixing chamber substantially enclosing the tapering walls of said oil mixing chamber and adapted to mix the atomized oil with said solid fuel, and a series of air chambers for regulating the air admitted into the furnace.

80 6. A fuel burner comprising an oil nozzle, an air nozzle surrounding said oil nozzle, rotatable atomizing means mounted within said oil nozzle, means for rotating said atomizer, air controlling means mounted rearwardly of said air nozzle for regulating the amount of air to be mixed with the atomized oil, and a plurality of partially telescoping air chambers for regulating the admission of air into the furnace.

85 7. A fuel burner comprising an oil nozzle, an air nozzle, a solid fuel nozzle, said oil nozzle being mounted within said air nozzle, rotatable atomizing means mounted in said oil nozzle for atomizing the oil passing therethrough, an air supply valve for regulating the air in said air nozzle, said valve being positioned rearwardly of said air nozzle.

zle, said solid fuel nozzle surrounding the forward end of said air nozzle and adapted to mix the solid fuel with the atomized oil, and a series of converging air chambers 5 mounted forwardly of said solid fuel nozzle for regulating the air admitted to the furnace with said fuel mixture.

8. A fuel burner comprising the combination of an oil nozzle, a rotatable atomizer in 10 said nozzle, means for rotating said atomizer, an air nozzle surrounding said oil nozzle, and an air supply valve for regulating the air entering said air nozzle, a fan for supplying air under pressure to said air 15 nozzle, a solid fuel nozzle adapted to receive the forward end of said air nozzle therein for mixing the atomized oil and air with the solid fuel, a plurality of air regulating chambers for controlling the air admitted 20 to the furnace with said fuel mixture, and means for mounting the device in a furnace door opening.

9. A fuel burner comprising an oil nozzle, a rotatable atomizer in said nozzle, 25 means for rotating said nozzle, an air nozzle adapted to mix air with the atomized oil, controlling means for determining the

amount of air to be mixed with the atomized oil, a solid fuel nozzle mounted forwardly of said air nozzle and adapted to receive the 30 air and atomized oil therefrom for mixing with the solid fuel, a plurality of air passages mounted forwardly of said solid fuel nozzle, a flange mounted about said solid fuel nozzle and extending outwardly therefrom, and a plate for holding the flange in adjusted position within the furnace door opening.

10. A fuel burner comprising an oil nozzle, rotatable atomizing means mounted on 40 said oil nozzle, means for rotating said atomizing means, an air nozzle surrounding said oil nozzle, air pressure means for supplying air to the air nozzle under pressure, valve means for regulating 45 the pressure of the air, a second fuel nozzle adapted to receive the atomized oil and air for mixture, a series of converging air regulating chambers for controlling the air admitted to the furnace with said fuel 50 mixture, and means for mounting the device in a furnace door opening.

CORNELIS ZULVER.
